UNITED STATES PATENT OFFICE.

CHARLES E. MORRIS, OF LEAVENWORTH, KANSAS, ASSIGNOR TO CHARLES W. PARKER,
OF LEAVENWORTH, KANSAS.

CAROUSEL.

1,241,138.

Specification of Letters Patent. Patented Sept. 25, 1917.

Application filed November 16, 1916. Serial No. 131,697.

To all whom it may concern:

Be it known that I, CHARLES E. MORRIS, a citizen of the United States, residing at Leavenworth, in the county of Leavenworth 5 and State of Kansas, have invented a certain new and useful Improvement in Carousels, of which the following is a specification.

My invention relates to improvements in carousels.

10 It relates particularly to the type of carousels provided with a revoluble frame which carries a support for a person and which is provided with means for imparting to said support a movement relative to the frame 15 when the frame is revolved.

As such carousels are ordinarily constructed, the relative or secondary movement of the support for the person is initiated simultaneously with the revolving of the 20 frame. A great strain is thus placed upon the operating mechanism which imparts an uneven and jerking movement to the frame and the support for the person carried thereby.

25 The object of my invention is to provide a carousel of the kind described in which the revolving movement of the frame and the secondary movement of the support for the person will be initiated one after the 30 other, thus throwing the entire load gradually upon the operating mechanism.

In the preferred form of my invention, a structure is provided in which the revolving movement of the frame is first initiated, 35 means, preferably manually operated, being provided by which the secondary movement of the support for the person may be initiated either simultaneously with the revolving movement of the frame or after the 40 frame is under way.

The novel features of my invention are hereinafter fully described and claimed.

In the accompanying drawings, which illustrate the preferred embodiment of my 45 invention,

Figure 1 is a view of my improved carousel shown partly in elevation, partly in vertical section and partly broken away.

Fig. 2 is a cross section on the line 2—2 of 50 Fig. 3.

Fig. 3 is an enlarged central vertical sectional view of a central portion of my improved carousel, on the line 3—3 of Fig. 4.

Fig. 4 is a horizontal section on the line 55 4—4 of Fig. 3.

Fig. 5 is a cross section on the line 5—5 of Fig. 3.

Similar reference characters designate similar parts in the different views.

A stationary support is provided comprising, preferably, a vertical tubular stand 1 which has its lower end secured to and supported by a horizontal base 2, on which are supported the lower ends of inclined bars 3, the upper ends of which support a stationary sleeve 4 which encircles the standard 1. 65

Supporting means, comprising, preferably, a revoluble frame consisting of the following described parts, is provided.

Revoluble on and supported by the sleeve 70 4 is a hub 5, in which are secured and supported the inner ends of a plurality of radial bars 6, which are also supported by inclined rods 7, the upper ends of which are fastened to a revoluble ring 8, Fig. 1, encircling the 75 standard 1 and resting upon a collar 9 secured to said standard adjacent to the upper end thereof.

A horizontal annular platform 10 which encircles the standard 1 is supported by rods 80 11, the upper ends of which are secured to and supported by the bars 6.

The frame which I have just described may be revolved by any suitable means, not shown, around the standard 1. 85

A plurality of radial shafts 12 are rotatably mounted respectively on the bars 6 in bearings 13 carried by said bars.

In the drawings, two kinds of rotary shafts are provided, one kind being denoted 90 by 12 and the other by 14. The shaft 12 is provided with a crank 15 which imparts vertical movement to a support for a person comprising a seat 16 carried by a vertical rod 17, the upper end of which is pivoted to 95 the crank 15.

The shaft 14 has secured to it a bevel gear wheel 18 which meshes with a bevel gear wheel 19 which is supported by a sleeve 20 mounted on the adjacent bar 6. The gear 100 wheel 19 is adapted to rotate on a vertical axis a support for a person, comprising a seat 21 supported by a vertical rod 22, which extends through the sleeve 20 and has secured to its upper end the gear wheel 19. 105

For rotating the shafts 12 and 14, said shafts have secured to their inner ends respectively pinions 23 which mesh with a horizontal gear wheel 24 which is rotatable upon the sleeve 4, and which is supported by 110

a bearing ring 25 encircling and supported by the sleeve 4, Fig. 3.

Means, preferably manually operated clutch mechanism, is provided for releasably locking the gear wheel 24 to the stationary sleeve 4. When the gear wheel 24 is thus locked and the frame carrying the seats 16 and 21, which are relatively movable to said frame, the pinions 23 will be made to travel around the gear wheel 24, thereby rotating the shafts 12 and 14 and thus vertically moving the seat 16 and rotating the seat 21.

For locking the gear wheel 24 to the sleeve 4, the following described frictional clutch mechanism may be employed.

The upper side of the gear wheel 24 is provided with an annular groove 26, in which are located two substantially semi-circular clutch members 27 having one set of ends pivoted to a vertical pin 28, the upper end of which extends into and is secured to a collar 29 which encircles and is rigidly secured to the standard 1 just above the gear wheel 24.

When the free ends of the clutch members 27 are forced apart and against the gear wheel 24, said clutch members will lockingly engage the gear wheel 24 and will hold it from rotation on the sleeve 4.

For releasing the clutch members 27 from the gear wheel 24, there is provided a horizontal transverse coil spring 30, the ends of which are respectively secured to the clutch members 27, the tension of the spring being such that it will normally tend to draw the free ends of the clutch members 27 toward each other and out of engagement with the gear wheel 24.

For forcing the clutch members 27 into locked engagement with the gear wheel 24, the following described mechanism may be employed.

A vertical rock shaft 31 is pivotally mounted in bearings 32 secured to the inner wall of the standard 1. Rigidly secured to the rock shaft 31 is a horizontal handle 33 which extends laterally through a slot 34 provided in the standard 1.

Secured to the upper end of the rock shaft 31 is a pinion 35 which extends through a slot 36 in the standard 1 and collar 29 and meshes with an intermediate pinion 37 which is rotatable on a vertical pin 38, the lower end of which is secured in the collar 29. The intermediate pinion 37 meshes with a pinion 39 which is rigidly secured to the upper end of a rotatable vertical pin 40 which extends through the collar 29 and has secured to it below said collar and in the groove 26 a block 41, which is square in cross section, and which is located in a space provided between the free ends of the clutch members 27. When the block 41 is in the position shown in dotted lines in Fig. 5, the clutch members 27 will be freed

by the spring 30 from the gear wheel 24. When the block 41 is turned to the position shown in solid lines in Fig. 5, it will strike and force apart the free ends of the clutch members 27, and will cause the clutch members to tightly clamp and lockingly engage the gear wheel 24. When the handle 33 is in the position shown in solid lines in Fig. 2, the clutch members will be forced by the block 41 to the locked position shown in Fig. 5. When the handle 33 is in the position shown in dotted lines in Fig. 2, the block 41 will be in the neutral position shown in dotted lines in Fig. 5, and the spring 30 will then release the clutch members 27 from the gear wheel 24.

In the operation of my invention, the frame carrying the seats 16 and 21 has its revolving movement initiated. After the frame is underway in its revolving movement, the operator may, at any time, swing the handle 33 from the position shown in dotted lines in Fig. 2, to the position shown in solid lines in said figure. The rock shaft 31 will thus be rocked, thereby turning the block 41 into the active position shown in Fig. 5, in solid lines, through the intermediacy of the pinions 35, 37 and 39 and the pin 40. The clutch members 27 will thus be forced into locked engagement with the gear wheel 24 and will thereby hold said gear member stationary. The revolving of the frame will cause the pinions 23 to rotate, due to their engagement with the gear wheel 24, thereby rotating the shafts 12 and 14, and through the intermediacy of said shaft and the intermediate connecting mechanisms imparting secondary movement to the seats 16 and 21, the seats being respectively vertically oscillated and rotated on a vertical axis.

As the entire load will be gradually placed upon the operating mechanism, there will be a minimum of strain thereupon and the starting of the mechanism into operation will be smoothly effected.

I do not limit my invention to the structure shown and described, as modifications, within the scope of the appended claims, may be made without departing from the spirit of my invention.

What I claim is:

1. In a carousel, revoluble supporting means; a support for a person carried thereby and adapted for movement relative thereto, operating means adapted to be actuated by said supporting means for imparting such relative movement to said support, and controlling means for gradually rendering said operating means active or inactive irrespective of the speed of movement of said supporting means.

2. In a carousel, revoluble supporting means; a support for a person carried thereby and adapted for movement relative

thereto, operating means adapted to be actuated by said supporting means for imparting such relative movement to said support, and including a frictional clutch mechanism 5 connecting said supporting means and said operating means, means for rendering said operating means active or inactive.

3. In a carousel, revolute supporting means, a support for a person carried there- 10 by and adapted for movement relative thereto, operating means actuated by said supporting means for imparting such relative movement to said support, and controlling means by which the operating means 15 may, at the option of the operator, gradually initiate such relative movement of the support irrespective of the speed of movement of said supporting means.

4. In a carousel, revolute supporting 20 means, a stationary support therefor, a member revolute on said support, releasable means for locking said member to said support, a support for a person carried by said revolute supporting means and adapt- 25 ed for movement relative thereto, and means permanently connecting said revolute member and said support for a person for im- parting such relative movement to said last named support when the revolute member 30 is locked to said stationary support.

5. In a carousel, revolute supporting means, a stationary support therefor, a gear wheel revolute on said support, releasable means for locking said gear wheel to said 35 support, a pinion meshing with said gear wheel, a support for a person carried by said revolute supporting means and adapt- 40 ed for movement relative thereto, and means actuated by said pinion for imparting such relative movement to said last named support.

6. In a carousel, revolute supporting means, a stationary support therefor, a member revolute on said support, releas- 45 able means for locking said member to said support, a rotary shaft on said supporting means, a support for a person movable by said shaft relatively to said supporting means, and means actuated by said revolute 50 member when the latter is locked to said stationary support for rotating said shaft.

7. In a carousel, revolute supporting means, a stationary support therefor, a gear wheel revolute on said support, releasable means for locking said gear wheel to said 55 support, a rotary shaft on said supporting means, a pinion meshing with said gear wheel and rotatable with said shaft, and a support for a person movable by said shaft.

8. In a carousel, revolute supporting 60 means, a stationary support therefor, a gear wheel revolute on said support, releasable means for locking said gear wheel to said support, a rotary shaft on said supporting means having a crank, a pinion meshing 65 with said gear wheel and rotatable with said shaft, and a support for a person connected with and movable by said crank.

9. In a carousel, revolute supporting means, a stationary support therefor, a 70 member revolute on said support, clutch mechanism for releasably locking said member to said support, means for operating said clutch mechanism, a support for a person carried by and movable relatively to 75 said supporting means, and means actuated by said revolute member when the latter is locked to said stationary support for so relatively moving said support for a person.

10. In a carousel, revolute supporting 80 means, a stationary support therefor, a gear wheel revolute on said support, manually operated clutch mechanism for releasably locking said gear wheel to said support, a rotary shaft on said supporting means, a 85 pinion meshing with said gear wheel and rotatable with said shaft, and a support for a person movable by said shaft.

11. In a carousel, revolute supporting means, a stationary support therefor, a gear 90 wheel revolute on said support, manually operated clutch mechanism for releasably locking said gear wheel to said support, a rotary shaft having a crank on said sup- 95 porting means, a pinion meshing with said gear wheel and rotatable with said shaft, and a support for a person carried by said supporting means and movable by said crank.

In testimony whereof I have signed my 100 name to this specification.

CHARLES E. MORRIS.
